RECEIVING ARRANGEMENT WITH APERIODIC DIRECTIONAL AERIAL SYSTEM

Application filed June 19, 1924, Serial No. 720,894, and in Germany June 27, 1923.

My invention relates to directional receiving systems as used in the radio art and it has for its object to provide a receiving system which employs an aperiodic directional aerial system capable of receiving different wave lengths simultaneously by the use of non-reactive couplings between the aperiodic aerial system and the receiving circuits tuned for the desired wave lengths.

10 Other objects will be apparent to those skilled in the art from the following description and claims, when considered with the accompanying drawings, in which:

Fig. 1 represents a circuit embodying my 15 invention used for multiplex directional receiving with a loop.

Fig. 2 represents a circuit embodying a different form of my invention with provision for one-way directional receiving.

20 The prior and usual receiving arrangements for wireless telegraphy and telephony which used aperiodic directional aerials, required means to compensate for the reactive effect of one goniometer upon the other.

25 This system required the two tuned circuits of each search coil system to be made exactly equal in inductance, capacity, resistance and mutual inductance. The disadvantage of this system lies in the difficulty exactly equalizing the two tuned circuits.

According to the present invention one single aerial can be used for simultaneously receiving several wave lengths by connecting the common aerial system across non-reactive 35 couplings to several receivers tuned to different frequencies. The principle of the invention is explained by Fig. 1 which shows such an arrangement. The two cross frame aerials *k* form the receiving aerial system.

40 The incoming oscillations are led in the known way from these frame aerials to the circuits *a* and *b* and from there to several receiving goniometers *l*, *m*, *n* across several non-reactive coupling arrangements which

45 are marked *c*. Coupled to the goniometers are receiving circuits *O*, *P*, *Q*. As the cross frame aerials *k* and the circuits *a* and *b* are aperiodic, they can be used for transferring different frequencies. Disturbing reactions 50 of the receiving circuits tuned to different

frequencies are eliminated, as the syntonizing means for the single frequencies are arranged behind the receiving goniometers which are connected to the aerial system across the non-reactive vacuum tube couplings *c*. The drawings show an arrangement for multiplex directional receiving.

A wave, therefore, oscillating in the circuit "a" may be impressed by means of tubes *R* and *R'*, *S* and *S'* and by means of the divided goniometer *l* on receiver *O*. Receiver *O* may be tuned to a different frequency without affecting receivers *P* or *Q* since no feedback reaction or detuning effects are produced by coupling thru the valve circuits. 65 It will be apparent then, that it will be possible to receive a different signal on any one of the three receiving circuits, for example *O* independently of and without affecting other signals received simultaneously in the 70 indicating circuits *P* and *Q*.

If the intention is to attain a unidirectional receiving for the different frequencies each frame aerial effect must be combined with a high aerial effect, that is, for every 75 frequency to be received a special non-directional aerial must be arranged from which the aerial effect is led to the corresponding receiver in order to obtain the required receiving characteristic for that frequency. 80

Fig. 2 shows an arrangement which can be used according to the invention for a simultaneous unidirectional receiving for different wave lengths λ_1 , λ_2 , and λ_3 . Every receiving circuit is supplied with an additional non-directional aerial effect, so that a special non-directional or vertical aerial is required for every wave length. As shown by the drawings, the earthed frame aerial *A*₁ can also be used as a vertical aerial for one 85 of the wave lengths, but special vertical aerials *A*₂, *A*₃ are necessary for the other wave lengths. The aerial effects are led from these aerials across the circuits *K*₁, *K*₂ and *K*₃ to the receiving circuits 1, 2 and 3 respectively while the frame aerial effects are transferred by means of a common circuit *K* and non-regenerative vacuum tube couplings indicated by *c* to the corresponding 95 receiving circuits. 100

Having described my invention what I claim is:

1. In a multiplex directional receiving system, a pair of directional aerials, each being responsive to a plurality of frequencies, a plurality of receivers adapted to be tuned to different frequencies and a separate electron valve circuit coupling each of said aerials to each of said receivers.
2. In a radio directional receiving apparatus an aperiodic directional aerial, a coil connected to said aerial, a second coil inductively connected therewith, a plurality of electron tubes, the ends of said second coil being connected to the grids of a plurality of pairs of electron tubes, the center of said coil being connected to the filaments of said electron tubes, a plurality of goniometers, the output circuit of each pair of tubes being connected to opposite ends of a goniometer coil, a source of plate potential applied to the center of each goniometer coil, and a tuned receiving circuit connected with the search coil of each goniometer.
3. In a radio system, an aerial arrangement comprising a plurality of directional aerials each being responsive to a plurality of frequencies, a coupling means connected to said aerial arrangement, a plurality of receivers adapted to be tuned to different frequencies, a plurality of pairs of electron tube amplifier circuits for coupling said aerial arrangement and said receivers through said coupling means, and having output coils, certain corresponding electrodes of said tubes being connected to opposite portions of said coupling means.
4. In a radio signalling system, an aperiodic directional antenna, a plurality of radio-goniometers with rotatable search coils, a plurality of receivers each connected with the rotatable search coil of a goniometer and adapted to be tuned to different frequencies and a plurality of electron valve amplifier circuits each comprising a double tube system having input and output circuits each input circuit being associated with said antenna and each output circuit being associated with a radiogoniometer coil and a receiver.
5. In a radio signalling system, a crossed loop aerial system, a plurality of electron valve circuits, connected to said loop aerial, a plurality of radiogoniometers connected to said electron valve circuits each having a pair of stationary coils and a rotatable coil, a stationary coil of each of said radiogoniometers being connected through the electron valve circuits with one of the loops of the aerial and an independently tuned receiving circuit connected with each rotatable coil of said radiogoniometers.
6. In a radio system, an aerial arrangement comprising a directional antenna responsive to a plurality of frequencies, a plurality of receivers adapted to be tuned to

different frequencies, a plurality of pairs of symmetrical electron tube amplifier circuits for coupling said aerial arrangement and said receivers and an individual non-directional antenna connected to each of said receiving circuits.

7. In a signalling circuit an aerial arrangement comprising a directional antenna responsive to a plurality of frequencies and a plurality of individually and independently tunable open antennae, a plurality of receivers adapted to be tuned to different frequencies a plurality of electron tube amplifier circuits for coupling said directional antenna to all of said receivers, a coupling circuit interposed between each amplifier and each receiver, variable tuning means in each of said coupling circuits, and means for coupling each of said receiving circuits with one of said open antennae.

8. An aperiodic frame aerial system, an inductance in series therewith, a plurality of groups of thermionic tubes, an inductance coupled with said series inductance, connections respectively between the terminals of said inductance and the control grids of the tubes in each group, a connection between the midpoint of said inductance and the filament of each tube, an output circuit connecting the output electrodes of the tubes in each of said groups, inductive means to couple a receiver to each output circuit, and means to tune said inductive means to signal frequency.

9. In a radio signalling system, a directional antenna system responsive to a wide band of frequencies, a plurality of receivers adapted to be tuned to different frequencies, a plurality of electron amplifiers each having their input elements coupled to said directional antenna, a separate output circuit connected with the output elements of each of said thermionic amplifiers, a separate link circuit interposed between each of said output circuits and one of said receivers, means for tuning said link circuit, and means for introducing nondirectional antenna energy in each of said receiving circuits.

10. In a multiplex directional receiving system, a directional aerial system including a closed frame aerial, said closed frame aerial forming a capacity area and a connection between said aerial and ground, a plurality of thermionic amplifiers each having an input circuit inductively coupled to said closed frame aerial, a plurality of receivers, separate symmetrical output circuits connected with each of said thermionic amplifiers, a coupling circuit interposed between each of said output circuits and a receiver, and tuning means in said last named circuit.

11. A bilateral multiplex receiving system comprising a pair of crossed frame aerials, an inductance connected in series with each of said aerials, a plurality of groups of thermionic tubes, each group comprising pairs

of thermionic tubes, an inductance coupled to each of said series inductances, means for connecting each terminal of each of said inductances to a grid electrode of a different tube in each pair of tubes, a plurality of radiogoniometers each having a field winding connected with the output electrodes of a pair of tubes in each of said groups of tubes, a search coil connected with each of said radiogoniometers, and a receiver connected with each search coil.

12. A unilateral multiplex receiver comprising a frame aerial, an inductance in series therewith, a connection between said aerial and ground, tuning means comprising an inductance and a variable capacity in said connection, a plurality of receivers, a circuit coupling said last named inductance to one of said receivers, a plurality of nondirectional aerials, tuning means in each of said aerials, a circuit for coupling each of said nondirectional aerials to a separate one of said receivers, an inductance coupled to the inductance in said frame aerial, a plurality of 25 pairs of thermionic tubes, a connection between the grid electrode of a tube in each of said pairs and one terminal of said last named inductance, a connection between the grid electrode of the other tube in each of said pairs and the other terminal of said last named inductance, an output circuit for each of said pairs of tubes, a coupling circuit interposed between each of said output circuits and a different one of said receivers, and 30 means for tuning each of said coupling circuits.
